(57) CLAIM

An ornamental design for a cloth-covered stuffed ball depicting a three dimensional image, as shown and described.

DESCRIPTION

FIG. 1 is a front view of the completed cloth-covered, stuffed ball showing a sample of a three dimensional image on the outer surface of the ball.

The broken lines in the FIGURE is for illustrative purposes only and forms no part of the claimed design.

1 Claim, 1 Drawing Sheet

FIG. 1
